UNITED STATES PATENT OFFICE

SAMUEL STOPHLET, OF KANSAS CITY, MISSOURI.

DESIGN FOR A WATCH-CHARM, &c.

SPECIFICATION forming part of Design No. 27,421, dated July 27, 1897.

Application filed August 7, 1896. Serial No. 602,086. Term of patent 3½ years.

To all whom it may concern:

Be it known that I, SAMUEL STOPHLET, of Kansas City, Jackson county, Missouri, have invented a new and original Design for Watch-Charms, &c., of which the following is a full, clear, and exact description, reference being had to the accompanying drawings, forming a part hereof.

The leading feature of my design consists in a disk-shaped figure bearing the representation upon the obverse side of an eagle and upon the reverse side of a number of slots or panels.

In the drawings, Figure 1 represents a view of the obverse side of the watch-charm, pocket-piece, or badge. Fig. 2 represents a view of the reverse side of the same.

Referring to said drawings in detail, 1 designates a disk-shaped figure, apparently recessed or paneled, as shown at 2, and occupying the central and lower portion of said

panel is the representation of an eagle. At the opposite or reverse side of the disk are two segmental panels 3 3, extending concentrically with respect to the axis of the disk, 25 and a rectangular panel 4 between them and at one side of the center of the disk. These panels are adapted to contain any suitable words. At a point in the periphery of the disk is the representation of an arm or handle 30 5.

What I claim is—

The design for a watch-charm, pocket-piece or badge, substantially as herein shown and described.

In testimony whereof I affix my signature 35 in presence of two witnesses.

SAMUEL STOPHLET.
